UNITED STATES PATENT OFFICE.

FREDERICK KOCH, OF NEWARK, NEW JERSEY, ASSIGNOR TO U. S. TOOL COMPANY, INC.,
A CORPORATION OF NEW JERSEY.

VERNIER CONDENSER.

Application filed April 28, 1924. Serial No. 709,397.

My invention relates to variable condensers, such as now generally used in radio-telephony and telegraphy, and it has for its object the provision of an improved form 5 of reduction gear train for changing the quick knob rotation into a materially slower rotor rotation, whereby the requisite capacity adjustments may be effected without the use of supplemental rotor and stator plates. 10 Another object is to provide an improved form of spacing washer which will accurately space the several plates of the condenser, and also aid materially in the rapid assembly of the parts in the process of 15 manufacture.

Other minor objects and improvements will be disclosed in the following detailed description in connection with the accompanying drawings, wherein,

20 Fig. 1 is a plan view of the complete condenser.

Fig. 2 is a section on line II—II of Fig. 1, showing the bottom frame plate and gear train in plan.

25 Fig. 3 is a plan of the top plate with the turning knob and index plate or dial removed.

Fig. 4 is a section through the central shafts and through the gear train.

30 Fig. 5 is a section of the rotor shaft, showing the form of the rotor plates and the spacing washers for separating the same.

Fig. 6 illustrates the method of forming 35 the washers in a helical coil upon a mandrel, and thereafter serving them by a single cut in a line parallel with the axis of the helix.

Fig. 7 is a plan of a washer upon the mandrel preparatory to upsetting the same to 40 form the flattened side.

Fig. 8 is an edge view of a washer.

Fig. 9 is a section on line IX—IX of 45 Fig. 3.

Fig. 10 is a section on line X—X of Fig. 2.

Fig. 11 is a plan of one of the rotor plates.

45 Figure 12 is a fragmentary view similar to Figure 2 but showing a modified form of star spring and support.

Figure 13 is a fragmentary sectional view similar to Figure 9 indicating a glass panel.

Similar reference numerals refer to like 50 parts throughout the specification and drawing.

The condenser consists of the frame for supporting the stator plates and for pivotally supporting the rotor. The frame is 55 made up of the top plate 1, the bottom plate 2, and the posts or bolts 3, 4, 5. Upon these bolts are mounted the several stator plates 6, spaced apart by the spacing washers 7, and from the plates 1 and 2 by the hexagon 60 spacing washers 8, which are of a thickness of at least three times that of the washers 7. The bolts 3, 4, 5 are insulated from the two plates 1 and 2, by means of the laminated mica insulation 9 and the mica 65 washers 10, 11, placed as shown under the bolt head and between the washers 8 and the respective plates 1 and 2. A similar method in insulation is employed for the threaded end of the bolts and with their 70 holding nuts 12, as shown in Fig. 10. The bolt holes are considerably larger than the bolts, and are filled with the small mica washers, and the larger disks of mica effectively protect the nuts from contact with 75 the metal of the frame plate.

The rotor consists of the central tubular shaft 13, upon which the semicircular plates 14 are secured. The shaft 13 is made of any form of rod which is polygonal in cross-section, that shown being hexagonal. Such a rod is turned down at each end to cylindrical form, so as to leave the original polygonal shape for a distance equal to the complete or combined thickness of all of the 80 plates with their spacing washers 15 when assembled, so that the clamping collar 16 at the upper or outer end serves as an abutment against which the first plate may rest, while the gang of plates and washers are 85 held firmly clamped by the nut 17 screwed on the threaded part of the other end of the shaft. The rotor plates 14 and the shaft 13 are mounted between the end plates 1, 2, so as to interleave said plates between 90 the stator plates 6. It will be noted that the holes in the rotor plates are of the same shape as the cross-section of the shaft, so

as to form a fairly close fit thereon. This enables me to assemble the rotor plates very quickly and in proper position without the use of the usual assembling gigs, and when 5 the nut 17 is screwed up all of the plates are accurately aligned. This simple construction reduces the time occupied in assembling the rotor parts from one third to one half, resulting in a materially increased 10 output per each operative, and a correspondingly reduced cost of manufacture.

The spacing washers hitherto universally used have been the usual punched washers, and in assembling the stator and rotor, it 15 has been necessary to line up the sets of washers to be used upon gig posts, because of the varying thickness of the individual washers; otherwise, it would be found that the aggregate thickness of one gang of 20 washers would vary from another, or that a slight burr upon one washer would throw an entire gang out of true with another gang. Much time has been spent in assembling the plates to get them all accurately 25 spaced, and so that the plates of the rotor will properly interleave with the plates of the stator. To overcome this difficulty, and secure accurate parallelism of the plates of both rotor and stator, I make the spacing 30 washers 7 and 15 of wire of suitable gage. The wire is first passed between heavy rollers to provide flattened surfaces upon opposite sides; it is then wound upon a mandrel, as 18, in the same manner as is used 35 to form helical springs, but with the flattened faces of the wire in contact. A longitudinal cut is then made parallel to the axis of the mandrel as at 19, thus severing the coil into as many separate washers as there 40 were convolutions in the entire coil. The individual washers 15 have their severed ends offset, as shown in Fig. 8; these offset ends are a distinct advantage in the assembled rotor or stator, for as the nuts 12 or 45 the nut 17 are screwed up, the otherwise warped washer is compressed flat and serves to hold the adjacent parts firmly in place, and themselves against shifting in substantially the same way as with the well-known 50 lock-washer. Another advantage from the use of the spacing washers as shown resides in the economy of material; there is practically no waste, since the wire from which the washers are made is all used, whereas, 55 in the cut or punched washer, more than half of the material goes into scrap. This material economy amounts to a large sum when the enormous number of condensers made and used is considered.

60 Another improvement of the condenser resides in the form of so-called "pig-tail" connection, or lead for the rotor. Upon the rotor shaft 13, just outside of the plate 1, is a metallic spool 20, with fiber or bakelite flanges 21. Upon this spool is the strip of

covered coil conductor 22, with its inner end firmly secured to the metal spool and its outer end fastened to the double ended clip 23, which is secured to the plate 1 by the screw 24. The lead wire 25 is fastened to the other end of the clip, as shown. The turning of the shaft 13 coils and uncoils the spiral spring-like connector 22, without in any way affecting the positive metallic connection between the outside lead wire 75 and the rotor plates. This is a very material advantage in devices of this kind, for the reason that the contact connections hitherto used have rendered the condensers subject to unforeseen capacity losses, and when it 80 is considered that the currents used are very weak, any capacity loss, however slight, becomes a serious matter when absolute accuracy is the very thing to be attained.

In order to still further reduce capacity 85 losses in the condenser, I effect a more intimate metallic connection between the several rotor plates 14 and the spacing washers 15 with the shaft 13, by dipping the entire rotor in a very thin bath of molten tin, so 90 as to give the rotor a complete metallic coating. The same result may be accomplished by immersing the rotor in a nickel or silver plating bath, or in fact any metallic plating bath, and coating the entire surface of 95 the rotor with a continuous layer of metal. These capacity losses are so minute and so elusive that it is often hard to determine just where they come from; but by the improvements set forth, I have been able to so 100 reduce them that they become negligible, even with the weakest current susceptible of measurement.

Condensers of the type described are usually mounted upon a panel, as 26, with the 105 end of the shaft 13 projecting beyond the face of the panel, and having the dial 27 secured thereto. The dial is indexed as at 28, for registry with the usual fixed pointer upon the panel, so that the dial may be turned, 110 to effect the required capacity adjustments. In practice, however, these adjustments are required to be very fine, much more minute than can be ordinarily effected by the simple turning of the dial by the usual knob. In 115 order to effect these finer adjustments, I have designed a simple form of reduction gear train, whereby a single turn of the knob will produce but a fraction of a turn of the dial and rotor. The dial 27 has a central apertured boss 29, through which the rotor shaft is inserted and secured by the set screw 30. It will be noted that the shaft 13 does not extend through the end plate 2, but only a short distance beyond the 120 clamping nut 17. Through the shaft 13 extends the vernier or driving shaft 31 with its inner end journaled in the plate 2, and its outer end extending beyond the outer end of shaft 13 and having secured there- 125 130

to the turning knob 32. Upon the shaft 31, just inside the plate 2, is secured the small pinion 33, and upon the stub shaft 34 a large gear wheel 35 is mounted to freely 5 rotate in mesh with the pinion 33. Upon the stub shaft 34 is the small pinion 36, held in frictional engagement with the gear wheel 35 by the star spring 37. Upon the end of the shaft 13 is the rigidly secured large 10 gear wheel 38, in mesh with the pinion 36. By the construction described it will be seen that the rotation of the shaft 31 by means of the turning knob 32, will be communicated to the shaft 13, through the pinion 15 33, the gear wheel 35, pinion 36 and gear wheel 38, but at a ratio depending upon the relative diameters of the pinions and gear wheels. The stub shaft 34 is secured to the plate 2 by the nut 39 which is screwed 20 upon the protruding end of the shaft. The shaft is provided with an eccentric bearing for the wheel 35 and pinion 36, so that by loosening the nut 39, the shaft may be turned to properly adjust the wheel and 25 pinion into proper mesh with the pinion 33 and wheel 38, in order to take up all of back-lash, and avoid any lost motion in the gear train. The end play of the shaft 31 is prevented by the rigidly secured pinion 30 upon the inside of the plate 2 and collar 40 upon the outside of said plate.

The same results are accomplished by the structure illustrated in Fig. 12, wherein the shaft 13, the shaft 31, the pinion 33 and 35 gear wheel 38 are the same as illustrated in Fig. 2. The gear 35, pinion 36, with the star spring 37 and stub shaft 34", are carried upon the free end of the arm 49, the latter being supported upon a post 34' 40 which is secured in the end plate 2. The coil spring 50 is wound around the post 34', with one of its ends bearing against a stud 51, inserted in the end plate 2, and and its other end 50' bearing against the 45 outside of the swinging arm 49; the purpose being to press the teeth of the pinion 36 into close engagement with the gear 38, and the gear 35 into similar engagement with the pinion 33, to overcome any back-lash. The safety pin 52 is inserted into 50 the plate 2, as shown, to limit swing of the arm 49 so that the pinion 36 and gear 35 cannot be swung outside of the edge of the plate 2. The purpose of the structure is, 55 as above set forth, to maintain a close engagement of the said gears and pinions when turning of the knob 32 to make the requisite adjustments.

In the use of variable condensers of the 60 type above described it has been the practice to make the frame plates 1 and 2 of some insulating composition as vulcanized rubber, fiber, bakelite, and condensite or the like. Careful tests of instruments provided 65 with such end plates show that there is a

capacity existing between the metallic plates 1 and 2, and plates 6 and 14 if such end plates are in any way connected with any of the outside circuits of the condenser a material loss of current is shown, particularly if the rotor is turned to produce minimum capacity measurements that the loss be reduced to as low a point as is possible. For that reason the end plates 1 and 2 are shown as removed to a distance from the 75 stator plates.

I have made the further discovery that it is possible to further insulate the end plates when such plates are made of such insulating material as vulcanized rubber, 80 fiber, bakelite, or other recognized insulating material. This is done in the manner shown in Fig. 13, wherein all of the parts are the same as those shown in Fig. 9 with the exception of metal plate 1. In place 85 of which I use any of the above insulating materials as may be desired. The post 3 the plates 6 spacing washers 7 and 8 are the same as is also the mica washers 9, 10, and 11. The same form of insulation should be 90 applied to the post 3 as shown in Fig. 10 by the substituting of insulating material for the plate 2. When thus contracted the most accurate tests with the most delicate testing instruments available have failed to 95 show any capacity existing between the plates 6 or 14 and end plates 1' and 2'. This in effect amounts to insulating an insulating material.

The plate 1 is provided with the three 100 posts 41, 42, and 43, by which the condenser is secured to the panel 26. It is also provided with the two stop posts 44, 45, which are engaged by the stop pin 46, projecting from the side of the spacing collar 47 upon 105 the shaft 13. In this manner, the rotor is limited in its rotation to a half rotation, that being sufficient to completely interleave its plates with those of the stator, or to swing the rotor plates completely free of inter-leaving relation with said stator plates. If upon turning the knob 32 until the stop pin 46 engages either one of the stop posts, a further turn is attempted, no harm can be 110 done to the instrument, for the frictional engagement of the pinion 36 and wheel 35 will slip, and thus all liability to injury 115 is obviated.

From the foregoing description, it will be 120 seen that the results obtained from the improved construction, while apparently insignificant when taken separately, yet in the aggregate, indicate that the principal, if not practically all of the sources of capacity losses have been taken care of and 125 removed; at the same time, the improvements are such as to materially reduce manufacturing costs to a minimum.

Minor changes coming within the scope of 130 the appended claims are contemplated.

I claim:—

In a variable condenser, the combination of a supporting frame, a rotor shaft mounted therein, said shaft having a polygonal cross-section for a portion of its length, a plurality of rotor plates having apertures therethrough to fit the polygonal section of

said shaft, and spacing washers surrounding said shaft between said plates, said washers each being formed of a single convolution of flattened wire and having its off-set ends inwardly bent to conform to a face of said polygonal shaft. ¹⁰

FREDERICK KOCH.
